VERNIER FRICTION KNOB

Filed April 29, 1925

Technical drawing of a device assembly, likely a lock or fastener, featuring a central vertical shaft (5) and a housing (6). The assembly includes a pin (11), a lock body (13), a lock plate (14), a lock ring (15), a lock cap (16), a lock base (17), a lock sleeve (18), a lock cap (19), a lock cap (20), a lock cap (21), a lock cap (22), a lock cap (23), a lock cap (24), a lock cap (25), and a lock cap (26). The drawing is signed "Harry L." at the bottom right.

UNITED STATES PATENT OFFICE.

HARRY L. BRADLEY, OF MILWAUKEE, WISCONSIN, ASSIGNOR TO THE RELIANCE COMPANY, OF MILWAUKEE, WISCONSIN, A CORPORATION OF WISCONSIN.

VERNIER FRICTION KNOB.

Application filed April 29, 1925. Serial No. 26,662.

This invention relates to certain new and useful improvements in vernier friction knobs especially adapted to revolve radio dials at an even speed slower than that possible by direct control, to thus facilitate fine tuning.

It is a general object of this invention to simplify and improve the construction of vernier friction knobs.

A further object of this invention is to provide an improved vernier friction knob having a mounting stud adapted to be fixed to the panel and a knob proper adapted to be readily secured over the stud and held against accidental detachment by a friction member or rubber washer which is adapted to be engaged with the periphery of the adjacent tuning dial.

With the above and other objects in view which will appear as the description proceeds, my invention resides in the novel construction, combination and arrangement of parts substantially as hereinafter described and more particularly defined by the appended claims, it being understood that such changes in the precise embodiment of the hereindisclosed invention may be made as come within the scope of the claims.

In the accompanying drawing, I have illustrated one complete example of the physical embodiment of my invention constructed according to the best mode I have so far devised for the practical application of the principles thereof, and in which:

Figure 1 is a perspective view of a radio front panel and a tuning dial equipped with one of my improved vernier friction knobs, the panel being broken away and but a portion of the dial shown, and

Figure 2 is a view taken through Figure 1 on the plane of the line 2—2, parts thereof being in section and parts in elevation.

Referring now more particularly to the accompanying drawing in which like numerals designate like parts, the numeral 5 designates the front panel of a radio receiving set which may be of any character having one or more tuning dials 6 rotatably mounted on the exterior thereof. The dials are connected with and control variable condensers or other parts and preferably have a beveled peripheral edge 7 provided with suitable graduations.

In tuning a radio set, it is often desirable to move the dials 6 at an extremely slow, even speed and this is impossible without the

means of a vernier attachment. In the drawing, I have illustrated an improved vernier attachment 8 which is adapted to be mounted on the panel adjacent the peripheral edge of each dial so that a slow even turning motion may be readily imparted to the dial.

The vernier attachment comprises a stud 9 having a flange 10 spaced from its inner end which forms a sleeve or collar 11 adapted to fit in an opening 13 formed in the panel 5, the stud being secured in position by a screw 14 inserted from the rear of the panel and threaded in the bore 15 of the stud. The outer end of the stud is enlarged to form a head 16 which is slidable in the bore 17 of a knob 18.

The knob 18 preferably has its outer peripheral edge 19 knurled to facilitate turning and its inner end is reduced and channeled, as at 20, to provide a flange 21 behind which the inwardly extending flange 22 of a friction member 23, such as a rubber washer or the like, is engaged. The inner end 24 of the friction member closes the bore of the knob and has an opening therein of a diameter to have a snug fit about the stud shank portion and cooperate with the abrupt shoulder 25 formed at the juncture of the head and shank portion to prevent the accidental dislodgment of the knob.

As will be readily apparent, the stud 9 is mounted on the panel 5 at the proper place and the knob 18 is readily pushed thereover and held in place by the friction member 23, the beveled outer end 26 of the head 16 facilitating the slipping of the friction member thereover. The inner peripheral edge of the friction member is preferably slightly beveled, as at 27 to insure a good contact with the dial and when the friction member is formed of rubber, live rubber is preferable.

From the foregoing description taken in connection with the accompanying drawing, it will be readily apparent to those skilled in the art to which an invention of this character appertains, that I provide a very novel and improved vernier knob which is simplified to facilitate manufacture and which is very convenient of application to radio sets.

What I claim as my invention is:

1. A device of the character described, comprising a mounting stud, a knob rotatable on the stud, a friction member carried by the knob, and yieldable means rotatably se-

curing the knob on the stud and permitting the ready detachment of the knob from the stud by the exertion of an outward pull thereon.

5. A device of the character described, comprising a mounting stud, a head formed on the outer end of the stud, a knob having a central bore to receive the stud head, whereby the knob is rotatably mounted on the head, and means including a friction member carried by the knob for securing the same on the stud, said stud head providing a broad bearing for the knob.

10. A device of the character described, comprising a mounting stud, a head formed on the end of the stud, a knob having a central bore to receive the stud head and rotatably mounted thereon, a friction member carried by the knob, and cooperating means 15 formed by the friction member and the stud head to prevent the accidental dislodgment of the knob from the stud.

15. A device of the character described, comprising a mounting stud having a shank portion and an enlarged portion outwardly 20 of the shank portion to form a head, the inner end of the head terminating in an abrupt

shoulder, a knob having a central bore to receive the stud head, and a friction member secured over the inner end of the knob and 30 having a bore of a diameter less than that of the stud head and registering with the knob central bore, whereby outwardly movement of the knob on the stud is limited by the friction member abutting the stud head shoulder. 35

20. A device of the character described, comprising a mounting stud, having a shank portion and an enlarged portion outwardly 40 of the shank portion and forming a head, the inner end of the head terminating in an abrupt shoulder, a knob having a central bore of a diameter to receive the stud head, and a friction member of yieldable material secured over the inner end of the knob and 45 having a bore of a diameter less than that of the stud head and registering with the knob central bore, whereby the knob may be pushed over the stud head and held in place on the stud by the friction member abutting the head shoulder, said shoulder defining the 50 outward limit of movement of the knob.

In testimony whereof I affix my signature.

HARRY L. BRADLEY.
